CLAIM

The ornamental design for a display screen or portion thereof with graphical user interface, as shown and described.

DESCRIPTION

The sole FIGURE is a front view of a display screen or portion thereof with graphical user interface showing our new design.

The outermost dashed-dotted broken line depicts a boundary line of a display screen or portion thereof, and forms no part of the claimed design. The dashed broken lines depict text, icons, or the remainder of the graphical user interface, and form no part of the claimed design.

1 Claim, 1 Drawing Sheet
